ICEBREAKER FOR HIGHWAY
MAINTENANCE

William A. Lommen, Windom, Minn.

Application March 22, 1948, Serial No. 16,245

1 Claim. (Cl. 262—13)

1

My invention relates to a device for removing ice from flat surfaces, particularly road pavements and the like.

The primary object of my invention is the provision of a device of the class described which is inexpensive to construct, durable in use, effective in operation, and readily mobile.

Another object of my invention is the provision of a device which, when moved over a paved surface, will subject the ice thereon to repeated impact of beater elements sufficient to shatter the ice so that the shattered ice may be readily swept from the pavement.

Another object of my invention is the provision of a device as set forth which is provided with beater elements which may be adjustably moved toward and from the ground.

A still further object of my invention is the provision of means for rotating the beater elements at predetermined speeds independent of the speed of the vehicle.

A still further object of my invention is the provision of a device as set forth which includes a pair of rotary elements having beaters thereon, said rotary elements being offset longitudinally and laterally of the machine and having their adjacent ends so positioned one with respect to the other so that the distance between the beaters at the end of one of said drums and the beaters at the adjacent end of the other of said drums is not substantially greater than the distance between beaters on the same drum.

Other highly important objects and advantages of my invention will become apparent from the following detailed specification, appended claim, and attached drawings.

Referring to the drawings, wherein like characters indicate like parts throughout the several views:

Fig. 1 is a view in plan of my novel ice breaker;
Fig. 2 is a view in side elevation of the machine of Fig. 1;

Fig. 3 is an enlarged cross-sectional detail of one of the beater-equipped rotary drums of my invention, taken substantially on the line 3—3 of Fig. 1, some parts removed; and

Fig. 4 is an axial section, taken substantially on the line 4—4 of Fig. 3.

Referring with greater particularity to the drawings, the numeral 1 indicates, in its entirety, a rectangular frame, the front and rear members of which are designated by the numerals 2 and 3 respectively and the side members by the numeral 4. Frame 1 is mounted on ground wheels 5, one adjacent each corner, by means

which may be of any suitable type but as shown comprise lever-acting arms 6 to which the wheels 5 are journaled by means of stub shafts 7 and which are pivotally secured at their upper ends to brackets 8 as indicated at 9, and adjusting means such as screws 10. The screws 10 have threaded engagement with nuts 11 pivotally secured to the lower ends of the arms 6. The screws 10 are journaled at their intermediate portions in the frame 1 and are held against axial movements therein by stop collars 12 on opposite sides of a platform member 13 forming part of the framework 1 and covering the same. At their upper ends, the screws 10 are provided with hand cranks 14.

Intermediate the front and rear pairs of wheels 5 are a pair of cage-like drums 15 and 16 which are journaled on horizontal axes in bearing brackets 17 and 18 respectively by means of shafts 19 and 20 respectively. Bearing brackets 17 and 18 are secured fast to the underside of the frame 1 by means of headed bolts or the like 21. The rotary drums 15 and 16 each comprise axially-spaced end plates 22 joined by a plurality of circumferentially-spaced axially-extending bars 23 secured fast to the peripheral portions of the end plates 22. As seen particularly with reference to Fig. 4, the end plates 22 of rotor 15 are made fast to the shaft 19 by means of pins 24 extending through bosses 25 on the end plates 22 and the shaft 19. The rotor 16 is identical to rotor 15 and is secured to the shaft 20 in the same manner in which rotor 15 is secured to shaft 19. Beater elements preferably and as shown in the nature of link chains 26 are shown as being secured to the circumferentially-spaced bars 23 in longitudinally-extended rows which extend from one end of the bars 23 to the other end thereof in spaced relationship one to the other. As shown particularly by Fig. 4, the beater elements 26 are spaced apart with the elements on one bar 23 being staggered with respect to the beater elements secured to the adjacent bar, for a purpose which will hereinafter become apparent. Preferably and as shown, hammer elements or striking blocks 27 are secured to the free outer ends of each of the beater elements 26.

Referring to Figs. 1 and 2, it will be observed that, whereas the drums 15 and 16 are in laterally-spaced relationship one to the other, they are also staggered in the same horizontal plane. The lateral spacing between the drums is just sufficient to allow clearance between the movable parts thereof, while the longitudinal stagger between the drums must be sufficient to prevent

contact between the beater elements of one drum and the bearings 18 of the other. Preferably and as shown, the longitudinal stagger between the axes of the drums 15 and 16 is greater than the diameter of either one of the drums thereof. It will be noted that adjacent ends of the drums 15 and 16 are so positioned, one with respect to the other in a direction axially thereof, that the beater elements 26 of the two drums 15 and 16 make an almost uninterrupted pattern extending the combined lengths of the drums 15 and 16.

Mounted adjacent the rear end of the frame 1, preferably and as shown, on the platform member 13, is an internal combustion engine 28 having a speed change transmission gearing not shown but contained within a housing 29 and operated by a gear shift handle 30. A pulley 31 is mounted fast on the end of the drive shaft 32; and a belt 33 runs thereover and over a similar pulley 34 fast on an extension 35 of the shaft 19. The extension 35 is journaled at its outer end in a bearing 36 secured to one of the frame members 4. The drum 16 is driven from the shaft extension 35 through the medium of a belt 37 running over a pulley 38 fast on the shaft 20 and a similar pulley 39 secured fast adjacent the outer end of the shaft extension 35. By the means above-described, the drums 15 and 16 may be rotated at any predetermined speed independent of the speed of the wheels 5. For the purpose of moving the same over a stretch of road pavement, I provide a bifurcated hitching bracket 40 having aligned openings 41 therein for reception of a pin or other hitch member.

While my device may be made of any given width, preferably it is made to correspond approximately to the width of a single normal highway lane so that by runs in opposite directions, the transverse width of a highway may be completely cleared of ice without affecting the normal flow of traffic thereon. Under varying conditions of use, such as thickness of ice on the highway or the like, it may become necessary or desirable to lower or raise the drums 15 and 16 or either one thereof with respect to the road surface. This may be accomplished by adjusting the screws 10 by manipulation of the cranks 14. Likewise it may become necessary or desirable to increase the rate of rotation of the drums 15 and 16 without regard to the speed of the vehicle. As above pointed out, this may be accomplished by adjusting the rate of speed of the motor 28.

It should be obvious that, as the drums 15 and

16 are rotated, the beater elements 26 thereon are extended radially outwardly by centrifugal force and caused to strike the ice on the pavement with sufficient impact to shatter the same and loosen the shattered pieces therefrom. The shattering of the ice is further enhanced by the striking blocks or hammer elements 27 on the outer ends of the chains 26.

While I have shown a preferred embodiment of my invention as required by Section 4888 of the United States Statutes, it should be obvious that the same is capable of considerable modification without departure from the scope and spirit of the appended claim.

What I claim is:

In a device for removing ice from pavements and the like including a wheel-equipped frame, a pair of laterally-spaced parallel drums journaled for rotation on horizontal axes on said frame in spaced relation to the ground and in staggered relationship longitudinally of the frame, circumferentially-spaced longitudinally-extended rows of flexible beater elements secured to said drums and projecting radially outwardly therefrom under rotation of said drums, the flexible beater elements of one of said rows on each of said drums being longitudinally offset from the flexible beater elements of adjacent rows, and means for rotating said drums at pre-determined speeds independent of the speed of said wheels, and in which adjacent ends of the drums lie so closely in the same vertical plane that the longitudinal distance between the flexible beater elements on the end of one drum with respect to those on the adjacent end of the other of said drums is not substantially greater than the distance between adjacent flexible beater elements on the same drum.

WILLIAM A. LOMMEN.
